UNITED STATES PATENT OFFICE.

JOSEPH P. BOWLES, OF WEST NEW BRIGHTON, NEW YORK.

BUTTON.

Application filed August 24, 1921. Serial No. 494,938.

To all whom it may concern:

Be it known that I, JOSEPH P. BOWLES, a citizen of the United States, residing in West New Brighton, in the county of Richmond and State of New York, have invented certain new and useful Improvements in Buttons, of which the following is a specification.

My present invention relates to improvements in buttons, and the main object of the invention is to provide a button which is readily secured in place on a garment or article by needle and thread, the needle when inserted from the rear, or cloth side, of the button being always directed to a thread hole of the button for passing readily therethrough in the course of sewing the button on.

A feature of the invention is the provision of directing faces or guide faces in the button, so arranged that the point of the needle will contact obliquely therewith when the needle is inserted from the rear, or cloth side, whereby the needle is directed to a thread hole of the button.

Another feature is the provision of a cupped portion, or bell mouth portion, in the rear, or cloth side, of the button, for receiving the mass of thread composed of threads customarily wrapped around or twisted around transversely to the axial line of the button and around the mass of thread composed of all the threads which have passed through the thread holes, and which first mentioned mass of thread usually is located between the rear, or cloth side, of the button and the face of the cloth, thereby causing the button to stand off or be raised from the surface of the cloth or article. Whereas by providing the cupped or bell mouth portion this massed thread will instead pack into said cupped or bell-mouth portion and permit the rear, or cloth side, or base of the button to lie flat or snug on the surface of the cloth.

In the accompanying drawings which show one embodiment of my invention, and which form part of this specification, Figure 1 is a top or face view.

Figure 2 is a sectional view on the line 2-2 of Fig. 1, and

Figure 3 is a rear or cloth side view.

Similar reference characters denote similar parts throughout the several views.

My button, which is made of any suitable

composition or material, is provided with a front or outer side A, which, as shown, is sunken, but is not necessarily so, and a rear or cloth side B.

A plurality of thread holes, such as 10, 60 pass through the front face A of the button. The button has an interior chamber C which on the rear or cloth side B of the button is provided with a cupped or bell mouth portion 11 of greater diameter than 65 said chamber for receiving or packing therein the thread to permit the button to lie flush with the cloth. The bell mouth portion 11 of said chamber has outwardly curving sides or faces 12 which extend into said 70 chamber towards the front side of the button and merge in the thread holes 10, the intention being to provide deflecting faces which in the event of contact therewith of the needle N, when inserted from the cloth 75 side of the button near the sides 12, will deflect or direct the needle to a thread hole 10 without tendency of the needle to stick or catch in the sides.

The thread holes 10 are off-set radially 80 from a teat or projection 13, round in cross-section, having its base located in the line of the axis of the button adjacent to the face portion A, and its stem extending rearwardly into the chamber C and surrounded thereby, the sides or faces 14 of the teat curving inwardly and merging in a bluntly rounded point 15 which terminates substantially at the upper line of the cupped or bell mouth portion 11, the intention being to provide a 90 deflecting end and deflecting faces for the teat with which, in the event of the needle N contacting therewith when inserted from the cloth side of the button near the center of the bell mouth portion 11, will deflect 95 or direct the needle to a thread hole 10 without tendency of the needle to stick or catch in the point or sides of the teat.

The ribs 16, Fig. 3, extend from the teat or projection 13 at right angles to the axis 100 of the teat. The ribs 16 at their inner edges extend longitudinally of the teat 13 from the base thereof to near the point 15, and at their outer edges extend longitudinally of the chamber C and merge in the sides of 105 the bell mouth portion 11, the ribs 16 providing partitioning walls which form with adjacent portions of the curving sides 12 segmental guiding areas or chambers 17, each of which is appurtenant to a thread 110

hole 10 for confining the needle when inserted from the rear side of the button to such area or chamber and directing it to the thread hole appurtenant to the chamber.

Having thus described my invention it should be understood that there may be modifications thereof and variations therein without departing from the spirit of the invention or exceeding the scope of the appended claims.

What I claim is:

1. A button comprising, a front side with thread holes therethrough, a rear side, an interior chamber having an outwardly flaring mouth on the rear side of the button with deflecting side faces extending into said chamber and merging in the thread holes, and a teat surrounded by said chamber having its base at the front side of the button and its stem extending into said chamber and having deflecting side faces terminating in a deflecting point; the thread holes being off-set radially from the base of said teat; the deflecting side faces of said bell mouth and chamber and the deflecting point and deflecting side faces of the teat serving to direct the needle to a thread hole.

2. A button comprising, a front side with thread holes therethrough, a rear side, an interior chamber having a bell mouth portion of greater diameter than the chamber, the bell mouth portion having outwardly curving side faces extending into said chamber and merging in the thread holes, and a teat round in cross-section surrounded by said chamber having its base at the front side of the button and its stem extending into said chamber and having inwardly curving side faces terminating in a bluntly rounded point; the thread holes being off-set radially from the base of said teat; the curving side faces of said bell mouth portion and chamber and the bluntly rounded point and curving side faces of the teat serving to direct the needle to a thread hole.

3. A button comprising, a front side with thread holes therethrough, a rear side, an interior chamber having a bell mouth portion with deflecting side faces extending into said chamber and merging in the thread

holes, a teat surrounded by said chamber having its base at the front side of the button and its stem extending into said chamber and having deflecting side faces terminating in a deflecting point, and partitioning ribs arranged at right angles to the axis of the teat and extending longitudinally of the teat and said chamber and forming with adjacent side portions of said chamber segmental chambers appurtenant to the thread holes; the thread holes being off-set radially from the base of said teat; the deflecting faces of said bell mouth portion and chamber and the deflecting point and deflecting side faces of the teat serving to direct the needle to a thread hole; and said segmental chambers serving to confine the needle thereto when inserted from the rear side of the button and direct it to a thread hole.

4. A button comprising, a front side with thread holes therethrough, a rear side, an interior chamber having a bell mouth portion of greater diameter than the chamber, the bell mouth portion having outwardly curving side faces extending into said chamber and merging in the thread holes, a teat round in cross-section surrounded by said chamber having its base at the front side of the button and its stem extending into said chamber and having inwardly curving side faces terminating in a bluntly rounded point, and partitioning ribs arranged at right angles to the axis of the teat and extending longitudinally of the teat and said chamber and forming with adjacent side portions of said chamber segmental chambers appurtenant to the thread holes; the thread holes being off-set radially from the base of said teat; the curving side faces of said bell mouth portion and chamber and the bluntly rounded point and curving side faces of the teat serving to direct the needle to a thread hole; and said segmental chambers serving to confine the needle thereto when inserted from the rear side of the button and direct it to a thread hole.
